CARBURETER.

1,166,308.

Specification of Letters Patent.

Patented Dec. 28, 1915.

Application filed January 17, 1913. Serial No. 742,602.

To all whom it may concern:

Be it known that I, EMILE HENRI ARQUEMBOURG, of 71 Rue du Moulin Vert, in the city of Paris, Republic of France, have 5 invented Improvements in Carbureters, of which the following is a full, clear, and exact description.

The invention has for its object a system 10 of carbureter of the type called "multiple carbureter," comprising two carbureters which combine their actions so as to give at any moment the carburation suited to the proper operation of the motor as well when working at a reduced speed as when working 15 at high speeds.

The invention is characterized by the application to a constant level carbureter of a small secondary carbureter mounted in alinement with the axis of the needle valve 20 of the gasolene tank; the stem of this needle valve, which in this case is hollow, serves as a gasolene inlet pipe leading to the secondary carbureter and supports at its end the spraying nozzle of the latter. The mixing 25 chamber of the secondary carbureter opens in the shell of the slowing down throttle cock, so that by working the latter either the main carbureter or the secondary carbureter 30 may be optionally put into operation.

The accompanying drawings illustrate 35 by way of example a form of this type of carbureter.

Figure 1 is a side elevation thereof; Fig. 40 2 is an end view; Fig. 3 is a vertical section 5 made on line A—A of Fig. 2.

In these drawings: *a* designates the spraying nozzle of the main carbureter provided with a plurality of spraying holes *a'*, *b* is the gasolene tank, *c* the needle valve of the latter, *d* the float controlling said needle valve through the medium of levers *e*, *f* the air inlet of the main carbureter, *g* the supplementary ball air intake, *h* the shell of the throttle cock, *i* the plug of this cock.

The stem *c* of the needle valve is hollow and provided at its lower part with one or several orifices *c'* through which the gasolene can enter and rise. Within this hollow needle valve is placed the spraying nozzle *j* of the secondary carbureter; the stem of said spraying nozzle is provided with a flange *j'* resting on the upper end of the hollow needle valve *c*.

The mixing chamber of the secondary car-

bureter is constituted by a removable tube *k* 55 mounted upon the seat *l* perforated with a central hole through which air may enter and in which opens the spraying nozzle *j*. The seat *l* is integral with a sleeve *m* capable of sliding and rotating upon a hollow 60 stem *n* supported by the cover *o* of the tank *b*. A returning spring *p*, taking a bearing on the end of said hollow stem *n*, constantly tends to raise the sleeve *m* and, consequently, the seat *l*. Said seat *l* is provided with a 65 guide rod *l'* entering into a hole in the cover *o* of the tank and the purpose of which is to insure the register of the axes of the seat *l* and of the spraying nozzle *j*.

Through the hollow stem *n* passes a tickler *q* allowing to work by hand the float *d* of the gasolene tank; a returning spring *r* taking a bearing upon a cap screwed on an extension of the hollow stem *n* urges said tickler *q* upwardly.

The tube *k* abuts at its upper part and is held under the action of the spring *p* against the end of the bent passage *s* constituting an extension of the mixing chamber and formed in a boss *t* supported by the shell *h* 80 of the throttle cock. The horizontal branch of said bent passage *s* opens within the shell *h* through an orifice *s'* the diameter of which is slightly greater than that necessary for working at a reduced speed; this orifice is 85 uncovered or closed at will by the plug *i* of the cock, as explained hereafter; at its opposite end, said horizontal branch of the passage *s* is provided with a plug *u* which may be perforated with a gaged orifice *u'* 90 constituting a supplementary air inlet orifice.

In the boss *t* is provided a chamber *v*, in which can circulate a hot fluid (for instance the exhaust gases of the motor or the water 95 issuing from the radiator) adapted to heat the passage *s* for the purpose of insuring the volatilization of the gasolene previous to its admission to the throttle cock and consequently to the motor.

The communication of the orifice *s'* of the secondary carbureter with the pipe of the shell *h* upon which is mounted the pipe leading to the motor, is obtained by means of a notch *w* provided in the plug *i* of the 105 throttle cock. The said notch is arranged in such a manner that the plug *i*, in the position corresponding to the working at a reduced

speed (Fig. 3), completely closes the main carbureter and uncovers but partially the orifice s^1 of the secondary carbureter.

When, for putting in operation the main carbureter, the plug i is rotated in the direction of the arrow illustrated in Fig. 3, said plug finishes uncovering the orifice s^1 and at the same time opens the main carbureter; in consequence of the increase of the cross sectional area of the outflow orifice of the secondary carbureter, the proportion of gasoline, relatively to the air, sucked in by the motor increases by reason, as is well known, of the difference of inertia of air and gasoline; this excess of gasoline is used for enriching the air or the air too slightly carbureted supplied by the main carbureter at the time it is put into operation. In these conditions, the substitution of the secondary carbureter for the main carbureter may be effected without running the risk that the mixture, admitted to the motor, falls during this substitution, to a degree of carburation prejudicial for the proper working of the motor.

When the plug i is rotated in reverse direction to the arrow illustrated in Fig. 3, said plug closes both the main and secondary carbureters and thus allows of avoiding any consumption of gasoline when a motor car goes down a hill under the action of its weight.

The notch w may be more or less extended so as to allow of acting simultaneously or not on both carbureters by means of the plug i .

The carburation of the secondary carbureter may be varied by means of a plug u , by replacing the latter by another plug presenting an orifice having a suitably gaged diameter, the depression within this carbureter is regulated at will and, consequently the quantity of gasoline discharged by the spraying nozzle j will also be regulated.

The present device allows of easily and readily putting up and taking off the constitutive elements of the secondary carbureter either for visiting, cleaning or substituting them for others. In fact, by means of a pressure exerted upon the sleeve m , the seat l lowers, the tube k is no longer held and can then be removed; then, by lifting the seat l , so as to disengage the rod l' of the cover o and by causing it to rotate about the hollow stem n , ready access may be had to the spraying nozzle which can then be withdrawn from the hollow needle valve c ; the cover o , levers e , needle valve stem c and float d of the constant level may also be removed. The putting back into place of the elements is effected quite as easily by bringing back the seat l in the axis of the needle valve c and introducing the guide rod l' in the cover o ; then the tube k is put into place by first lowering the seat l and by al-

lowing it to rise again under the action of its spring. It is, moreover, to be noted that by means of the present device, the fixation of the cover o is perfectly insured by the reaction of the spring p .

It is to be understood that the form of device above described is given only by way of example and that the present device may be applied to any constant level carbureters and provided with a throttle cock.

Claims:

1. A carburation apparatus for explosion motors characterized by the combination of a main carbureter, a secondary carbureter, a carbureted mixture admission pipe and a throttle cock located in said admission pipe adapted to control both carbureters, a pipe connecting the secondary carbureter with the throttle cock through an orifice having a diameter greater than that calculated for running at slow speed, means for causing the throttle cock to partially uncover said orifice in the position corresponding to slow speed and to completely uncover said orifice when the throttle cock is turned to position corresponding to operating position for the main carbureter and to progressively close the secondary carbureter at such time, the whole combined to cause the secondary carbureter to give a mixture rich in gasoline to compensate for insufficient carburation of the mixture given by the main carbureter at the beginning of its operation.

2. A carburation apparatus for explosion motors, characterized by the combination of a main carbureter, a secondary carbureter, a throttle cock placed on the pipe for the admission of the carbureted mixture to the motor and adapted to control both carbureters, a pipe putting the secondary carbureter into communication with the throttle cock and opening in the latter through an orifice having a diameter greater than that calculated for running at slow speed, a notch provided on the plug of the throttle cock and adapted to uncover but partly, in the position corresponding to the running at slow speed, the orifice of the secondary carbureter, to uncover completely said orifice when said plug is turned in the position corresponding to the putting in to use of the main carbureter, and to gradually close the secondary carbureter at the time of the putting into use of the main carbureter.

3. A carburation apparatus for explosion motors characterized by the combination, a constant level feeding tank provided with a float, a hollow needle valve presenting at its lower part holes for the passage of the liquid fuel, a main carbureting chamber in communication with the constant level tank, a spraying nozzle through which the liquid fuel flows into the main carbureting chamber, a secondary carbureting chamber in which opens a spraying nozzle mounted on the hol-

- low needle valve, a throttle cock placed upon the inlet pipe leading to the motor and adapted to control the main carbureter and the secondary carbureter, a pipe putting the secondary carbureting chamber into communication with the throttle cock and opening in the latter through an orifice having a diameter greater than that calculated for running at slow speed, a notch provided on the plug of the throttle cock and adapted to uncover but partly, in the position corresponding to slow speed, the orifice corresponding to the secondary carbureting chamber, to uncover completely said orifice when said plug is turned in the position corresponding to the putting into use of the main carbureter, and to gradually close said orifice in proportion as it uncovers the orifice of the main carbureting chamber.
4. A carburation apparatus for explosion motors characterized by the combination: a constant level feeding tank provided with a float, a hollow needle valve presenting at its lower part holes for the passage of the liquid fuel, a main carbureting chamber in communication with the constant level tank, a spraying nozzle through which the liquid fuel flows into the main carbureting chamber, a secondary carbureting chamber in which opens a spraying nozzle mounted on the hollow needle valve, a throttle cock placed upon the inlet pipe leading to the motor and adapted to control the main carbureter and the secondary carbureter, a pipe putting the secondary carbureting chamber into communication with the throttle cock and opening in the latter through an orifice having a diameter greater than that calculated for running at slow speed, a stopper supported by said pipe and provided with a gaged supplementary air inlet orifice, a notch provided on the plug of the throttle cock and adapted to uncover but partly, in the position corresponding to slow speed the orifice corresponding to the secondary carbureting chamber, to uncover completely said orifice when said plug is turned in the position corre-
- sponding to the putting into use of the main carbureter, and to gradually close said orifice in proportion as it uncovers the orifice of the main carbureting chamber.
5. In combination, a main carbureter having a throttle cock, a secondary carbureter connected to said cock and opening in the latter through an orifice having a diameter greater than that calculated for running at slow speed, said throttle cock being constructed and arranged to close entirely both carbureters, to partially uncover the orifice of the secondary carbureter in the case of the running at slow speed, to open said orifice of the secondary carbureter at the time of the opening of the main carbureter and to progressively close the orifice of the secondary carbureter in proportion to the opening of the main carbureter.
6. The combination with a main carbureter having a constant level float feed chamber, a pointed shut-off valve in the feed chamber, said valve being hollow and provided with orifices, and a throttle valve having a notch or groove in its periphery, of a secondary carbureter connected with the throttle valve by a passage leading through the casing thereof and having a carbureting chamber, and a jet tube arranged in the hollow valve of the main carbureter and opening into the said carbureting chamber.
7. The combination with the feed chamber and throttle valve of a main carbureter, of a conduit leading from the throttle valve casing, a pivoted and spring pressed seat carried by the cover of the feed chamber and having an opening therein, a tube on the seat between the said seat and the end of the conduit, and a jet tube projecting into the opening of said seat.
- The foregoing specification of my improvements in carbureters, signed by me this 30th day of December 1912.
